Patented Sept. 1, 1914.

UNITED STATES PATENT OFFICE.

PARKE T. SNYDER, OF CHICAGO, ILLINOIS.

SHIPPING-PACKAGE.

1,108,937.

Specification of Letters Patent.

Patented Sept. 1, 1914.

Application filed March 19, 1913. Serial No. 755,478.

To all whom it may concern:

Be it known that I, PARKE T. SNYDER, a citizen of the United States, residing at Chicago, in the county of Cook and State 5 of Illinois, have invented certain new and useful Improvements in Shipping-Packages, of which the following is a specification.

My invention relates to improvements in shipping packages and more particularly, 10 in some of its features, to metallic shipping barrels.

One desideratum of a shipping package, which I attain by my invention, is to render the package strong and durable, and so to 15 effect the closure that its presence tends to increase the strength of the structure, and furthermore it is desirable that the construction be such that filling of the package, or the outward pressure due thereto, tends 20 rather to enhance the effectiveness of the closure than to detract therefrom.

My invention provides a package, the wall and heads of which may be formed wholly of sheet metal, wherein the joints between 25 connecting peripheral parts of the body and heads are substantially effected, the connecting parts being mutually stable when the package is closed, and readily accessible for emplacement or removal.

Furthermore, my invention provides a 30 package which is simple and strong in construction; cheap and easy of manufacture, involving only three major parts; capable of being closed many times without defacement or mutilation; and adapted to be 35 shipped or stored in knocked-down condition, when occasion demands, and to be used over and over many times.

Many other objects are provided for by 40 my invention, which will become apparent to those skilled in the art, from the following description and the accompanying drawings, wherein—

Figure 1 is an elevation with parts broken 45 away, showing a barrel or drum embodying my invention; Fig. 2 is a transverse sectional view on line 2—2 of Fig. 3; Fig. 3 is an enlarged section of a portion of the head and the side wall of the structure; and Fig. 50 4 is a detail of a staple used for holding the lapped side walls together, preliminarily to the emplacement of the heads thereon.

In all the views the same reference characters are employed to indicate similar parts. 55 It will be understood that while, in the following description, for the sake of

brevity, I refer to the structure simply as a barrel, many features of the construction may be employed and incorporated in other forms of packages with more or less of the 60 advantage herein referred to without departure from the spirit of my invention.

10 indicates in general the central body portion of the barrel preferably formed of a single piece of sheet metal that may be vertically corrugated, as at 11, throughout its entire periphery. While the drawing shows the walls in a straight vertical line it is, of course, apparent that they may take the form of a centrally swelled body of a bilge 70 barrel and still embrace or contain all the advantageous features present in the barrel wherein the side walls are in a straight vertical line, or as in the vessel of this character which is usually referred to as a drum. 75

The extremities of the body 10 are overlapped and are temporarily held together by means of a staple 13, of which there may be one or more at each end of the structure. The object of the staple is to hold the parts 80 in relation until the emplacement of the heads, after which the heads will serve to retain the body part in its desired circular form. Specifically, the respective inner and outer lapped-ends 12 and 12' of the 85 blank 10 overlap for the distance of several corrugations; the corrugations being nested, and the resiliency of the material permitting them to be brought into snug fitting relation, as shown in Fig. 2. 90

The heads of the barrel may be duplicates, each head 14 being arranged to effect an interlock with the outer peripheral edge of the barrel body by means of an insertible pin or key. Specifically, each head 14 95 provides an annular base 15, a central disk 16, displaced or dished inwardly to provide an abrupt interior shoulder 17, preferably inwardly inclined, surrounding the base 15, and a circumferential exterior rim or flange 18 providing between the walls 17 and 18 of the head an annular interior groove of width equal to the width of the corrugated surfaces of the body part 10. By this structure the disk 16 is inwardly displaced so as to 100 radially support the walls 10 and to provide a chime in the annular outwardly extended wall 17 and 18. By this arrangement a strong diametric support for the outer vertical walls of the vessel is provided to resist inward pressure and furthermore this arrangement displaces the main portion of 105 110

the closure, so that the weight of the barrel, and contents, will rest upon the base portion 15 while the inner wall 16 will be raised above contact with intervening obstructions. To give further strength to the disk or body portion of the closures 14, I may impress concentric beads 19 therein.

Near the outer upper edge of the body portion 10 of the structure, I impress or indent grooves or notches 20 as coöperating means for holding the closure in place. These grooves are shown as made in the exterior crests or faces of the outwardly turned, consecutive corrugations, as clearly 15 shown in cross section in Fig. 3, and are covered by the flange 18 of closure 14 when the latter is in place. In said flange, perforations 23 and 24, properly spaced apart, are made at intervals around the periphery 20 of the closure. These indented perforations correspond in the horizontal plane with the indentations 20 made in the body part of the barrel, so that when the heads or closures 14 are placed in position a nail, pin, 25 or other like key 25, may be driven through the perforations 23 and 24 and along a plurality of the indentations 20 of the body part of the vessel, thereby firmly and completely keying the closure with the body portion 30 of the structure. The perforations 23 and 24 are indented to such an extent that when the key 25, which for convenience may be a finishing nail of proper length and diameter, is driven through the said perforations, 35 the heads and points will lie within the indented portions 23 and 24 respectively, and will not project beyond the outer surface of the flange 18 so that the points and heads of the nail or key 25 are protected from contact with other objects.

In its elements, it will be observed that my package comprises only three parts, the body-blank and two heads. These may obviously be stored, shipped, or handled in 45 knocked-down condition; and to set up the barrel all that is requisite is to temporarily hold the lapped ends of the body-blank together, as by means of the staples or otherwise, and then slip on the heads and pass 50 the keys through the perforations that are made therein. The keys, as heretofore stated, may consist of ordinary nails, or of wires cut the proper length, so that should they be destroyed other keys may readily 55 be supplied from ordinary articles of commerce, such as nails or wires without requiring special accompanying keys. This is one of the features of value in the practice of my invention. It will also be apparent 60 that from the view point of the shipper, the structure could hardly be simpler of operation, as no tools whatever are necessary in setting up the barrel and after the body and

one head have been assembled and the barrel is filled the mere slipping on of the other 65 head and the insertion of two or three nails is all that is necessary to prepare the package for shipment.

While I have herein described in some detail a particular embodiment of my invention, and some of the details of which I will hereinafter claim for their specific benefit, it will be apparent that numerous changes may be made in the precise embodiment of the invention without departure from its 75 spirit and within the scope of the appended claims.

What I claim is:

1. A shipping package comprising a side wall having an imperforate groove near its 80 edge; a closure having an exterior flange overlying said groove; and having in said flange perforate indentations in substantially the same plane as said groove to receive a key which coöperates with the groove 85 in the walls to hold the parts together.

2. A shipping package comprising a side wall having an imperforate groove near its edge; a closure having an exterior flange overlying said groove, and having in said 90 flange a plurality of pairs of perforate indentations, spaced apart longitudinally of said flange, and substantially in the same plane as said groove, to receive keys which coöperate with the grooves in the walls to 95 hold the parts together.

3. A shipping package comprising a corrugated side wall having a series of notches in the outward crests of the corrugations, near its edge; a closure having an exterior 100 flange overlying said notches, and having in said flange perforate indentations in substantially the same plane as said notches, to receive a key which coöperates with the notches in the wall to hold the parts together.

4. A shipping package comprising a corrugated side wall having a series of notches in the outward crests of the corrugations, near its edge; a closure having an inset disk 110 part and an exterior annular bead portion, radially therebeyond, to provide an inner annular groove for reception of the edge of said side wall, and having an outward flange extending inwardly to inclose said 115 notches, and having in said flange perforate indentations in substantially the same plane as said notches, to receive keys which coöperate with the notches in the wall to hold the parts together.

In testimony whereof I hereunto set my hand in the presence of two witnesses.

PARKE T. SNYDER.

In the presence of—

FORÉE BAIN,

MARY F. ALLEN.
